Inventor:

Robert G. Utley.

UNITED STATES PATENT OFFICE.

ROBERT G. UTLEY, OF BOSTON, MASSACHUSETTS, ASSIGNOR TO CHARLES H. PIERCE, CHARLES H. GILMAN, AND GEORGE W. TUTTLE.

IMPROVEMENT IN MACHINES FOR MAKING EXTENSION-TABLE TOPS.

Specification forming part of Letters Patent No. **136,193**, dated February 25, 1873.

To all whom it may concern:

Be it known that I, ROBERT G. UTLEY, of Boston, in the county of Suffolk and State of Massachusetts, have invented a new and Improved Machine for Making Extension Tables; and I do declare that the following is a full and exact description thereof, which will enable others to understand and use the same.

The object of this invention is to provide a means whereby the boards used for filling in extension tables may be so made that every board shall be the perfect duplicate in all respects except width of every other board so made.

It is not designed to do the whole of the work of making the boards on this machine, but to correct all the imperfections that are unavoidable by the method heretofore employed.

In the accompanying sheet of drawing, Figure 1 is a top view of my invention. Fig. 2 is an end view of the same.

A and A' are forms corresponding in length and thickness to one of the boards used for filling. They are of wood, but have pieces of metal fastened to their inner edges, as shown by dotted lines in Fig. 1. b b b are pins projecting from the metallic edge of the form A' to engage with the holes in one edge of the boards to be operated upon. c c c are holes, shown by dotted lines, in the form A, and corresponding with the pins b b b to receive the dowel-pins in the opposite edge of the boards. g g g are springs to push the boards away from the forms when the board is to be removed. d and d are pieces of wood or metal raised above the surface of the forms, forming guides against which the sides of the plane used to remove the wood above the forms may slide.

From the above description it will be seen that to operate the machine a board, having the holes made in one edge to engage with the pins b b b; and provided with dowels at the other edge to correspond with the holes c c c, is inserted between the forms A and A' and grasped firmly by turning up the screw f. While it is held in this position the board is planed down until the side of the plane bears on the metallic edge of the forms A A'. The cutting-edge of the iron is kept from touching the form by its sides bearing against the raised gages d d, which are at a distance from the edge of the form just equal to the thickness of the wooden part of the plane outside the iron.

The ends of the board may be made to correspond with the form by any suitable means.

The board is removed from the machine by turning back the screws f, when the springs g g g will push the board away from the forms.

It will thus be seen that when any number of boards has been operated upon each edge of a board will be a perfect counterpart of every other corresponding edge, and that any board selected at random will match perfectly with any other and may be used in any table, thus rendering unnecessary any registry by numbers.

Having thus described my invention, I claim as new and desire to secure by Letters Patent—

The combination of the forms A and A' having pins b b b and holes c c c with guides d d, when operated in the manner and for the purpose specified.

R. G. UTLEY.
